UNITED STATES PATENT OFFICE

166,669

OVERDRIVE HOUSING

Harry F. Heisler, Hudson, Iowa

Application May 15, 1950, Serial No. 9,951

Term of patent 7 years

(Cl. D55—1)

To all whom it may concern:

Be it known that I, Harry F. Heisler, a citizen of the United States and a resident of Hudson, in the county of Blackhawk and State of Iowa, have invented a new, original, and ornamental Design for an Overdrive Housing, of which the following is a specification, reference being had to the accompanying drawing, forming part thereof.

Figure 1 is a front elevation of an overdrive housing, showing my new design and is taken looking toward the face of the overdrive housing through which the power is brought in;

Figure 2 is a top plan view of the overdrive housing and is taken looking downward on the housing shown in Figure 1;

Figure 3 is a side elevation view of the overdrive housing taken looking from the right of Figure 1;

Figure 4 is a side elevation view taken looking from the left of Figure 1; and

Figure 5 is a rear elevation view taken looking toward the face of the overdrive housing through which the power is taken out.

I claim:

The ornamental design for an overdrive housing, substantially as shown.

HARRY F. HEISLER.
